UNITED STATES PATENT OFFICE.

ANSON ATWOOD, OF TROY, NEW YORK, ASSIGNOR TO BENJAMIN STARBUCK, OF SAME PLACE.

DESIGN FOR A STOVE.

Specification forming part of Design No. 33, dated July 14, 1845.

To all whom it may concern:

Be it known that I, ANSON ATWOOD, of the city of Troy, county of Rensselaer, and State of New York, by my own industry, genius, and expense have invented and produced a new and original Design, Shape, Configuration, and Pattern of Stove-Plates to be Used in the Manufacture of Air-Tight Stoves, of which the following is a specification.

The nature of my invention consists in the peculiar shape, configuration, and ornamental carved work of the outer surface of the cast-iron plates forming the stove.

The stove is the usual form of cast-iron box-stoves, constructed so as to be air-tight, or as nearly so as practicable.

The outer surface of the plates consists of a colonnade or row of columns, *a a a a a a a*, on the side plate, seven in number, raised above the surface, so as to exhibit the front half of a round fluted column divided by rings or circles into three nearly-equal divisions or longitudinal sections, and fluted in each section. The surface of the plate between the columns (which are about two inches apart) is orna-

mented with a vine, *b*, intended to represent a grape-vine and grapes, raised or carved in basso-rilievo. The colonnade is surmounted by a capital consisting of a row of Gothic arches, *C*, brought forward so as to stand centrally on the tops of the columns, and having their front surfaces even with the front surfaces of the columns. The surface of the plate between and within said arches *D* is ornamented with small fanciful carvings, as represented in the drawing, and not susceptible of verbal description.

The above description is as perfect as I am able to make, reference being had to the accompanying drawing.

What I claim as my invention, and desire to secure by Letters Patent, is—

The design, shape, configuration, style, and ornamental carvings of the external surface of the plates of the stove.

ANSON ATWOOD.
